CLAIM

The ornamental design for an eye shield, as shown and described.

DESCRIPTION

FIG. 1 is a perspective view of an eye shield;

FIG. 2 is a front view of an eye shield;

FIG. 3 is a back view of an eye shield;

FIG. 4 is a left side view of an eye shield;

FIG. 5 is a right side view of an eye shield;

FIG. 6 is a top view of an eye shield;

FIG. 7 is a bottom view of an eye shield; and,

FIG. 8 is an in use view of an eye shield.

The broken lines in FIG. 8 show portions of the environment and form no part of the claimed design.
